(57) **CLAIM**

The ornamental design for an applicator and packaging assembly, as shown and described.

DESCRIPTION

FIG. 1 is an upper exploded perspective view of an applicator and packaging assembly showing my new design in an environmental use including a chemical composition in broken lines;

FIG. 2 is an upper perspective view of the applicator and packaging assembly;

FIG. 3 is a front elevation view of the packaging component of the applicator and packaging assembly for clarity of illustration;

FIG. 4 is a back elevation view thereof;

FIG. 5 is a front elevation view of the applicator component of the applicator and packaging assembly for clarity of illustration, a back elevation view being identical;

FIG. 6 is a side elevation view thereof, the opposite side elevation view, the end and opposite end views being identical;

FIG. 7 is a front elevation view of the applicator and packaging assembly of FIG. 2;

FIG. 8 is a back elevation view thereof;

FIG. 9 is a side elevation view thereof;

FIG. 10 is an opposite side elevation view thereof;

FIG. 11 is an end elevation view thereof; and,

FIG. 12 is an opposite end elevation view thereof.

The broken line portions of FIG. 1 are included for the purpose of illustrating use and environment and form no part of the claimed design.

The side, opposite side, end and opposite end elevation views of the foil wrapper component are not shown, and no claim is made to the side, opposite side, end and opposite end elevation views of the foil wrapper component.
